UNITED STATES PATENT OFFICE

152,054

DESIGN FOR A SHOWER HEAD

Ralph E. Bletcher and Ernest H. Bucknell, Los Angeles, Calif., assignors of ten per cent to Ralph E. Bletcher, twelve and one-half per cent to Ernest H. Bucknell, twelve and one-half per cent to Mabel Bucknell, ten per cent to Pearl White Bletcher, twenty-five per cent to Marcia Bucknell Liston, ten per cent to James H. Bletcher, ten per cent to Hazel Bletcher Skinner, ten per cent to Charlotte R. B. Robertson

Application November 26, 1946, Serial No. 135,108

Term of patent 3½ years

(Cl. D91—1)

To all whom it may concern:

Be it known that we, Ralph E. Bletcher and Ernest H. Bucknell, citizens of the United States, residing at Los Angeles, in the county of Los Angeles, State of California, have invented a new, original, and ornamental Design for Shower Head, of which the following is a specification, reference being had to the accompanying drawing, forming a part thereof.

We claim:

The ornamental design for a shower head, as shown.

RALPH E. BLETCHER.
ERNEST H. BUCKNELL.
